(57) **CLAIM**

The ornamental design for the combination lighting fixture backplate and lamp support arms, as shown and described.

DESCRIPTION

FIG. 1 is a side elevation view of the combination lighting fixture backplate and lamp support arms in accordance with our design, illustrating the environment for the backplate and lamp support arms;

FIG. 2 is a front elevation view of the backplate taken along Section 2—2 of FIG. 1.

FIG. 3 is a front elevation view of the combination lighting fixture backplate and lamp support arms in accordance with our design;

FIG. 4 is a side elevation view of the combination lighting fixture backplate and lamp support arms in accordance with our design; and,

FIG. 5 is a top plan view of the combination lighting fixture backplate and lamp support arms in accordance with our design.

The right and left elevation views are symmetrical. The top and bottom plan views are symmetrical. The rear elevation view is unornamented and follows the contours of FIGS. 2, 3 and 4.
